UNITED STATES PATENT OFFICE.

EDWARD C. HOCK, OF BUFFALO, NEW YORK

SMOKE-CONSUMING DEVICE FOR HEATERS OR BOILERS.

1,106,709.

Specification of Letters Patent. Patented Aug. 11, 1914.

Application filed October 1, 1913. Serial No. 792,794.

To all whom it may concern:

Be it known that I, EDWARD C. HOCK, a citizen of the United States, residing at Buffalo, in the county of Erie and State of New York, have invented certain new and useful Improvements in Smoke-Consuming Devices for Heaters or Boilers, of which the following is a specification.

My invention relates to smoke consuming devices for heaters, boilers and furnaces, and it has for its object the provision of a device of this kind which can be easily attached to any heater, boiler or furnace and be so located with reference to the fuel in the fireplace that it will direct jets of heated air into the fireplace so as to commingle with the unconsumed products of combustion and cause said products to become ignited.

Another object of my invention is to provide a smoke consuming device of this kind which will occupy a comparatively small space in the fireplace and which will not interfere with the feeding of fuel thereinto and will at the same time direct jets of heated air over an extended area.

A further object is to provide a smoke consuming device of this kind which will be of simple and inexpensive construction and in which air is directed from the exterior of the heater, boiler or furnace to a series of escape tubes.

With these and other objects in view, the invention consists in the novel features of construction and in the arrangement and combination of parts to be hereinafter described and more particularly pointed out in the subjoined claims.

In the drawings.—Figure 1 is a perspective view of a heater or boiler showing the same equipped with my improved smoke consuming device and having a portion of its wall broken away to illustrate said device within the fireplace. Fig. 2 is a horizontal section through the smoke consuming device and that portion of the wall of the heater or boiler supporting the same. Fig. 3 is a longitudinal section taken on line 3—3, Fig. 2. Fig. 4 is a transverse section of one of the air escape or distributing tubes. Fig. 5 is a central section through a modified form of hot air distributer. Fig. 6 is a vertical longitudinal section through the inlet tube showing a modified construction.

Referring now to the drawings in detail, similar numerals of reference refer to similar parts in several figures.

The reference 7 designates a heater or boiler having the usual fireplace 8, through the wall of which is passed an air inlet tube 9, said tube extending inwardly to a point near the center of the fireplace and having attached thereto an air distributer 10. Forming part of the air inlet tube is an injector 11 in the form of a casting, into the ends of which is threaded two sections 12, 13 of said inlet tube, said casting having an opening 14 in its bottom and a nozzle 15 centrally disposed therein and terminating at a point beyond said opening. The parts thus secured constitute the smoke consuming device. The air distributer 10, comprises a central portion 16 having a central opening 17 and an annular air passage 18. A wall separating said central opening from said annular air passage is provided with a plurality of air escape openings 19 and projecting outwardly from said central portion are radiating distributer or air escape tubes 20, the outer ends of which are closed and which have near said outer ends air escape openings 21, said tubes being preferably of triangular shape in cross section, as shown in Fig. 4, and the air escape openings therein being formed in the downwardly diverging walls of said tubes so as to cause the air from said tubes to be directed laterally and downwardly, whereby the jets of air are directed toward the fuel and over an extended area thereof. By thus directing the air jets from the radiating tubes they meet the rising unconsumed products of combustion and are thus thoroughly commingled therewith causing ignition of said products and complete consumption thereof.

It is to be noted that hot air from the fireplace enters the air inlet tube 9 through the opening 14 in the injector, and its entrance is accelerated by the exterior air escaping from the nozzle 15 in its passage therethrough. This hot air commingles with the exterior air in its passage through the inlet tube and distributer, and is further heated during such travel. The air escaping from the openings 19 in the wall separating the central opening of said distributer from the annular passage 18 therein commingles with any unconsumed products of combustion.

passing through said central opening, and by constructing the distributor as described the inrushing exterior air which is heated in its passage to and through the distributor 5 is ejected from the latter over almost the entire area of the burning fuel, assuring complete consumption of all gases and other unconsumed products escaping from the burning fuel.

10 In the modification shown in Fig. 5 the distributor has a central chamber 22 into which the inlet tube 9 enters from the bottom, the radiating distributor tubes 23 being in direct communication with said central chamber.

15 In the modification shown in Fig. 6 the inlet tube is provided with a nozzle 24 at its inlet end, said nozzle being threaded or otherwise fastened thereinto, and a second 20 nozzle 25 is located between said first-mentioned nozzle and the distributor, said second nozzle having one end enlarged and directed downwardly to or through an opening formed in said inlet tube. The air 25 passing inwardly through said inlet tube draws in the heated air from the fireplace while passing the end of said second nozzle, said heated air thoroughly commingling with the exterior air and heating the same 30 and said commingled air being further heated in its passage to and through the distributor.

Having thus described my invention, what I claim is,—

35 1. A smoke consuming device comprising a centrally located hollow annulus having air escape openings to direct the air to the axis of said annulus, horizontally-disposed radial tubes connected to said annulus and 40 having air escape openings, each of said tubes being of triangular formation in cross section and arranged to provide two downwardly-diverging walls in which said last-mentioned air escape openings are located,

and an air inlet tube connected to said centrally located annulus. 45

2. In a smoke consuming device adapted to be located in the fireplace of a heater, boiler or furnace, the combination of a distributor comprising a centrally-located hollow annulus and horizontally-disposed radial tubes extending from said annulus, said tubes and annulus having air escape openings, and an air inlet tube connected to said distributor and adapted to lead exterior air 55 to the latter, said inlet tube having an opening in the fireplace for the admission of hot air from the same, the hot air only being adapted to commingle with the exterior air in its passage to and through said distributor and the commingled bodies of air being adapted to be heated in their course to said air escape openings. 60

3. In a smoke consuming device adapted to be located in the fireplace of a heater, 65 boiler or furnace, the combination with a distributor comprising a centrally-located hollow annulus and horizontally-disposed radial tubes extending from said annulus, said tubes and annulus having air escape 70 openings, an air inlet tube extending from the distributor and adapted to pass through the wall of the fireplace to admit exterior air thereto, and an injector connected to said air inlet tube and comprising a casing 75 having a centrally-disposed air nozzle through which only the exterior air is passed, and an opening for the admission of hot air into the space surrounding said nozzle, the whole being arranged so that only hot air 80 and exterior air commingle in their passage to the distributor.

In testimony whereof I affix my signature in presence of two witnesses.

EDWARD C. HOCK.
